UNITED STATES PATENT OFFICE.

CHARLES G. GEIGER, OF ST. JOSEPH, MISSOURI.

ORTHOPEDIC AND FRACTURE-EXTENSION DEVICE.

1,216,434.

Specification of Letters Patent. Patented Feb. 20, 1917.

Application filed February 23, 1916. Serial No. 79,812.

To all whom it may concern:

Be it known that I, CHARLES G. GEIGER, a citizen of the United States of America, residing at St. Joseph, in the county of Buchanan and State of Missouri, have invented certain new and useful Improvements in Orthopedic and Fracture-Extension Devices, of which the following is a specification.

10 The object of my invention is to secure a continued extension of the arm, leg or body and at the same time to give clearance underneath the part being operated upon so that dressings may be applied without obstruction.

I accomplish my object by the mechanism illustrated in the accompanying drawings in which: Figure 1 is a perspective view of an old operating table with the new extension connected and in place; Fig. 2 is an end view of one section of the extension; Fig. 3 is a side view of one section of the extension; Fig. 4 is a top view of one section of the extension; Fig. 5 is an end view of the arm support; Fig. 6 is a side view of the arm support; Fig. 7 is a top view of the arm support; Fig. 8 is a front view of the saddle brace; Fig. 9 is a side view of the saddle brace; Fig. 10 is a side view of the chest brace; Fig. 11 is a top view of the chest brace; Fig. 12 is a bottom view of the chest brace; Fig. 13 is an end view of the chest brace; Fig. 14 is an end view of the foot piece; Fig. 15 is a side view of the foot piece; Fig. 16 is a top view of the hand piece; Fig. 17 is a bottom view of the hand piece; Fig. 18 is a side view of the hand piece, and Fig. 19 is an end view of the hand piece.

40 In said drawings A represents any style of operating table and B B are extensions thereof shown in operating position. C C are bolts which fasten tube M directly to an operating table. C' C' are bolts that pass 45 through female tubes E E and male tubes D D and which regulate the length of arms B B. F F are extension rods which pass through tubes G G. Tubes G G are provided with grooves g g in which set screws J J travel and prevent extension rods F F from turning. H H are nuts with handles h h on the extension rods. Between the nuts and extension tubes there are brass washers h' h'. I I are frames which are welded to 50 male tubes D D and also welded to tubes G G. The arm B with the taller frame I

is always used underneath the arm with the shorter frame I. K K are supports for an arm or leg while being operated upon. Supports K K can be shortened or lengthened; they are fastened to female tubes E E and can be moved in or out, as desired; they are fastened to female tubes by vise thumb nuts. k k are thumb nuts to regulate the length of supports h' h'. L L are 60 lugs on the inner ends of female tubes E E which support the female and male tubes and their accessories as shown in Figs. 1, 3 and 4. l l are set screws which pass through lugs L L and fasten said lugs to supporting 70 tube M. L' is a lug in which two rods M' M' are screwed. Rods M' M' are fastened to the sides of the operating table by two bolts (not shown). Lug L' is fastened to supporting tube M by set screw m. Saddle 75 N is provided with a rod N' which is welded to said saddle N. Said rod passes into tube M and the depth it passes into tube M is regulated by a set screw O. P is a support or rest for the head and shoulders of the 80 person being operated on. P' is a rod bent at right angles and welded to support P. The free end of rod P' passes into tube M and the distance that rod P' passes into tube M is regulated by set screw O. Q is a 85 steel side support for the body which holds the body when extension is made on the patient's arm. Q' Q' are combined bolts and thumb screws which fasten supports Q Q to rest P. R R are legs on rest P when 90 used to set on operating table while applying surgical dressings on the back and hips of the patient. S S are foot supports and S' S' are slotted plates of iron which pass into grooves on the inner ends of rods F F. 95 Said plates S' S' are welded to said supports S S. T T are supports for the patient's hands being fastened to supports S S when extension is made on a patient's arm.

100 What I claim and desire to secure by Letters Patent, is:

1. The combination with an operating table, of extension arms and an upright tube giving support to said extension arms, a 105 female tube, a male tube adapted to be telescoped into said female tube, extension rods and tubes through which said rods pass, set screws adapted to travel in grooves in said tubes to prevent the extension rods from 110 turning, and the nuts and handles on said extension rods.

2. The combination with an operating table, of extension arms and an upright tube giving support to said extension arms, a female tube, a male tube adapted to be telescoped into said female tube, extension rods and tubes through which said rods pass, set screws adapted to travel in grooves in said tubes to prevent the extension rods from turning, and the nuts and handles on said extension rods, the frames welded to the male tubes and to the tubes through which the extension rods pass, adjustable supports for an arm or leg fastened to said female tubes and thumb nuts to regulate the length of the supports, lugs on the inner ends of said female supports and set screws to fasten said lugs to the supporting tube, and rods fastened to the lower lug and to the sides of an operating table.

3. The combination with an operating table, of extension arms and an upright tube giving support to said extension arms, a female tube, a male tube adapted to be telescoped into said female tube, extension rods and tubes through which said rods pass, set screws adapted to travel in grooves in said tubes to prevent the extension rods from turning, and the nuts and handles on said extension rods, the frames welded to the male tubes and to the tubes through which the extension rods pass, adjustable supports for an arm or leg fastened to said female tubes and thumb nuts to regulate the length of the supports, lugs on the inner ends of said female supports and set screws to fasten said lugs to the supporting tube, and rods fastened to the lower lug and to the sides of an operating table, a support for the head

and shoulders of a person being operated upon and lugs on said support, a rod bent at right angles and welded to said support, a steel support to hold the body when extension is made on the person's arm, and suitable means to fasten the supports together.

4. The combination with an operating table, of extension arms and an upright tube giving support to said extension arms, a female tube, a male tube adapted to be telescoped into said female tube, extension rods and tubes through which said rods pass, set screws adapted to travel in grooves in said tubes to prevent the extension rods from turning, and the nuts and handles on said extension rods, the frames welded to the male tubes and to the tubes through which the extension rods pass, adjustable supports for an arm or leg fastened to said female tubes and thumb nuts to regulate the length of the supports, lugs on the inner ends of said female supports and set screws to fasten said lugs to the supporting tube, and rods fastened to the lower lug and to the sides of an operating table, a saddle and a rod welded to said saddle, and suitable means to fasten the supports together, foot supports and slotted plates engaging with the grooves in the inner ends of the extension rods, said plates being welded to said foot supports, and supports for the hand when extension is made on a person's arm.

In testimony whereof I affix my signature in the presence of two witnesses.

CHARLES G. GEIGER.

Witnesses:

B. L. LIBERMAN,
G. O. ARNOLD.
